UNITED STATES PATENT OFFICE.

GUSTAF DAVID SUNDSTRAND, OF ROCKFORD, ILLINOIS, ASSIGNOR TO ROCKFORD MILLING MACHINE COMPANY, OF ROCKFORD, ILLINOIS, A CORPORATION OF ILLINOIS.

MILLING MACHINE.

1,352,849.

Specification of Letters Patent. Patented Sept. 14, 1920.

Application filed April 30, 1919. Serial No. 293,869.

To all whom it may concern:

Be it known that I, GUSTAF DAVID SUNDSTRAND, a citizen of the United States, residing at Rockford, in the county of Winnebago and State of Illinois, have invented certain new and useful Improvements in Milling-Machines, of which the following is a specification.

Milling machines, as commonly constructed, comprise a column upon which a knee is vertically slidable, said knee carrying a horizontally movable saddle, and the saddle carrying a horizontally movable table. The column is provided with a base which projects beneath the knee. The means for vertically moving the knee comprises a screw and nut interposed between the knee and said projecting portion of the base.

To illustrate the difficulty which the present invention obviates, let us assume that the knee weighs, say 600 lbs.; the saddle perhaps 300 lbs.; and the table possibly 600 lbs. It may be further assumed that the saddle has been fed to the outer end of the knee and that there is a weight of perhaps 500 to 1000 lbs. upon the table. If now it is desired to raise the knee, say, one one-thousandth of an inch, the screw, when operated to produce this amount of movement, may, in fact, not move the knee at all, the base springing with reference to the column. The failure of the knee to move is due to a certain amount of binding between the knee and its guide on the column on account of the over-hanging weight. If the operator makes another attempt to move the knee one one-thousandth of an inch by again operating the screw, the resistance due to binding may be overcome, thus releasing the tension in the base and causing the knee to move through a distance of two one-thousandths of an inch.

The object of the present invention is to prevent such irregular and unreliable operation of the knee. This object has been obtained by the employment of means to stiffen the base and the column so as to prevent springing of the base with reference to the column.

In the accompanying drawing, Figure 1 is a fragmental side elevation of a milling machine embodying the features of my invention. Fig. 2 is a fragmental sectional view

taken in the plane of dotted line 2—2 of Fig. 4. Fig. 3 is a section on line 3—3 of Fig. 1. Fig. 4 is a section on line 4—4 of Fig. 1. Fig. 5 is a section on line 5—5 of Fig. 2.

In the drawings, 1 denotes the hollow column, said column having a vertical guide 2 upon its forward side upon which guide the knee 3 is mounted.

On the knee 3 is a saddle 4 movable toward and away from the column. The saddle carries a table 5.

The column 2 is provided with a base 6 having a portion 7 which extends forward beneath the knee. 8 is a screw interposed between the knee 3 and a bearing 9 on the base portion 7.

To stiffen the frame and prevent relative movement between the column 1 and the base portion 7, I provide within the lower portion of the hollow column a horizontal web 10 extending rearwardly from the front wall of the column, a vertical web 11 extending from the rear portion of the web 10 to the base 6, said webs 10 and 11 extending from one side wall of the column to the other, and a vertical web 12 extending from the front wall of the column to the web 11, and from the web 10 to the base, the web 12 being midway between the side walls of the column 1. The webs, 10, 11 and 12, being located within the angle formed between the front wall of the column and the base, serve to prevent relative movement between the column and the base when pressure tending to separate the knee 3 and the base portion 7 is applied. As shown in Figs. 2 and 5 the web 12 extends into the forwardly projecting portion 7 of the base, merging with the metal of the bearing 9, and reinforcing the sloping parts 16 of the base portion 7, to form a very rigid integral connection between the bearing 9 and the guide 2.

The space between the web 11 and the rear wall of the column is divided by a central vertical partition 13 into two compartments 14 and 15 which may be used as oil reservoirs or receptacles.

As will be understood, the column 1, the base 6 and the webs 10, 11, 12 and 13 constitute, in practice, a single casting. Webs 12 and 13, being in alinement, constitute a single rib, which, as shown in Figs. 2 and

4, projects below the flooring of the base, to form a depending flange 17 extending back to meet the transverse flange 18.

5 Diagonal reinforcing flanges 19 extend inwardly from the rear corners of the base as clearly indicated in Fig. 3 to a meeting point directly under the intersection of webs 11, 12 and 13 to distribute the stresses centered at this point by the meeting of the 10 webs.

15 While I have described and illustrated in detail a specific embodiment of my invention, it should be clearly understood that the description is only for purposes of illustration and that many modifications and variations will naturally occur to those skilled in the art. I aim in the subjoined claims to cover all such legitimate variations and modifications.

20 I claim as my invention:

1. A milling machine having, in combination, a hollow column having a front wall and two side walls, a base for the column, said base projecting forwardly of the column, a guide on the front wall of the column, a knee vertically slideable upon said guide, means for exerting force tending to separate the knee and said projecting portion of the base, a web extending rearwardly 25 from the front wall of the column and from one side wall of the column to the other, and a vertical web extending across the angle between the front wall of the column and the other web substantially midway between the two side walls of the column, said vertical web extending into the forwardly projecting portion of the base.

40 2. A milling machine having, in combination, a hollow column having a front wall, a base for the column, said base projecting forwardly of the column, a knee vertically slideable upon the forward side of the column, means for exerting force tending to separate the knee and said projecting portion of the base, and a vertical web within 45 the column and extending from the front wall of the column rearwardly so as to occupy the angle between said front wall and base, said web also extending into the forwardly projecting portion of the base.

55 3. A machine tool having, in combination, a hollow column, a base projecting in front of said column, and a vertical web in said column projecting forward uninterruptedly into the front portion of said base.

60 4. A machine tool having, in combination, a hollow column, a base projecting in front of said column, and a vertical web in said column projecting forward uninterruptedly 65 into the front portion of said base, said base comprising a horizontal floor structure having a central deformation of an inverted U-shape, the bight of said deformation being integrally united to the upper edge of said vertical web.

5. A machine tool having, in combination, a hollow column, a central web in said column, said web projecting in front of said column, and a base supporting said column and projecting in front of the same, said 70 base comprising a floor integrally united to the forwardly projecting portion of said web to furnish lateral support for the same.

6. A machine tool having, in combination, 75 a hollow column, a vertical web in said column, said web projecting in front of said column, a base supporting said column and integrally united to said web, and an additional horizontal web between the side walls of said column above the level of said base 80 bracing the upper edge of said vertical web to said side walls.

7. A machine tool having, in combination, 85 a hollow column, a vertical web in said column, said web projecting in front of said column, a base supporting said column and integrally united to said web, and an additional horizontal web within said column above the level of said base extending from the front wall of said column part way to 90 the rear wall and bracing the upper edge of said vertical web to the front wall and the front portion of the side walls of said column.

8. A machine tool having, in combination, 95 a horizontal column, a base projecting in front of said column, a longitudinal vertical web in said column projecting uninterruptedly forward into said base, a horizontal web bracing the upper edge of said vertical 100 web to the side walls of said column, and a transverse vertical web bracing said first-mentioned vertical web to the side walls of the column, to the base and to said horizontal web.

105 9. A machine tool having, in combination, a hollow column, a base supporting said hollow column and projecting in front of the same, a longitudinal vertical web in said column projecting uninterruptedly forward 110 into the front portion of said base, a horizontal web extending from the front wall of said column part way back and bracing the upper portion of said vertical web to the front wall and the front portion of the side 115 walls of said column, and a vertical transverse web extending downward from said horizontal web and bracing said longitudinal vertical web to the side walls of the column, to the horizontal web and to the base. 120

10. A machine tool having, in combination, a hollow column, a base supporting said column and projecting in front of the same, said base having a floor, and a vertical web within said column projecting uninterruptedly forward into said base, said web extending above and below the floor of said base. 125

11. A machine tool having, in combination, a hollow column, a base supporting said column and projecting in front of the same, 130

a longitudinal vertical web inside said column, and projecting uninterruptedly forward into said base, a transverse vertical web within said column intermediate front 5 and rear walls thereof bracing said longitudinal vertical web to the side walls, said base comprising a floor integrally united to said vertical webs, and diagonal reinforcing

flanges carried by the floor of said base and extending from the intersection of said floor 10 and said vertical webs diagonally rearwardly and outwardly to the rear corners of said base.

In testimony whereof, I have hereunto set my hand.

GUSTAF DAVID SUNDSTRAND.
